Primary Examiner — Michael A. Pratt

(74) *Attorney, Agent, or Firm* — Gerald E. Helget; Taft Stettinius & Hollister LLP

(57) **CLAIM**

The ornamental design for a reversible, accessories adaptable archery bow sight, as shown and described.

DESCRIPTION

FIG. 1 is a top plan view;

FIG. 2 is a bottom plan view;

FIG. 3 is a left side elevational view;

FIG. 4 is a right side elevational view;

FIG. 5 is a rear elevational view;

FIG. 6 is a front elevational view;

FIG. 7 is an upper front perspective view;

FIG. 8 is a lower rear perspective view with a shadow visor in phantom outline captured at the rear of the bow sight by the rear knurled threaded ring;

FIG. 9 is a lower left perspective view;

FIG. 10 is a front right side perspective view with a lighted shadow visor in phantom outline captured at the front of the bow sight by the front knurled threaded ring;

FIG. 11 is a front right side perspective view with a shadow visor in phantom outline captured at the front of the bow sight by the front knurled threaded ring and a shade tube in phantom outline captured at the rear of the bow sight by the rear knurled threaded ring;

FIG. 12 is a front right side perspective view with a shadow visor in phantom outline captured at the front of the bow sight by the front knurled threaded ring and a fiber optics sight tube in phantom outline captured at the rear of the bow sight by the rear knurled threaded ring;

FIG. 13 is an upper front perspective view with a lens in phantom outline captured at the front of the bow sight by the front knurled ring; and,

FIG. 14 is a front perspective view with the fiber optics sight pin in phantom outline.

The bow sight accessories show in phantom outline form no part of the invention and are shown for illustrative purposes only.

1 Claim, 3 Drawing Sheets
